United States Patent

Des. 239,946

Patented May 18, 1976

239,946

ELECTRONIC MACHINE FOR USE IN DOCUMENT PROCESSING

Robert L. Greene, Diamond Bar, and Lorin P. Olson,
Tustin, Calif., assignors to Addressograph-Multigraph
Corporation, Cleveland, Ohio

Filed Aug. 1, 1974, Ser. No. 493,492

Term of patent 14 years

Int. Cl. D14—02

U.S. Cl. D26—5 C

Fig. 1

Fig. 2

FIG. 3

FIG. 4

FIG. 1 is a top, front and left side perspective view of an electronic machine for use in document processing, showing our new design.

FIG. 2 is a top, rear and right side perspective view.

FIG. 3 is a left side elevational view.

FIG. 4 is a front elevational view.

We claim:

The ornamental design for an electronic machine for use in document processing, as shown.
